[57] CLAIM

The ornamental design for a golf swing training aid, as shown and described.

DESCRIPTION

FIG. 1 is a perspective view of the golf swing training aid, showing my new design in its most compact mode;

FIG. 2 is a top plan view thereof;

FIG. 3 is a rear elevational view thereof;

FIG. 4 is a front elevational view thereof;

FIG. 5 is a bottom plan view thereof;

FIG. 6 is a right side elevational view thereof;

FIG. 7 is a left side elevational view thereof;

FIG. 8 is a top plan view showing my new design in its most expanded mode; and,

FIG. 9 is a bottom plan view of the golf swing training aid as shown in FIG. 8.

FIG. 1

FIG. 2
